RIDING TOY FIGURE

Laurie Jay Campbell, Erie, Pa., assignor to Louis Marx
& Company, Inc., New York, N.Y., a corporation of
New York

Filed Jan. 3, 1969, Ser. No. 15,232

Term of Patent 14 years

The portion of the term of the patent subsequent
to Dec. 3, 1982, has been disclaimed

Int. Cl. D21—02

U.S. Cl. D34—15

FIG. 1

FIG. 2

FIG. 3

FIG. 4

FIG. 5

FIG. 6

FIG. 1 is a side elevational view of a riding toy figure in accordance with my new design;

FIG. 2 is a top plan view thereof;

FIG. 3 is a front view thereof;

FIG. 4 is a rear view thereof;

FIG. 5 is a bottom plan view thereof, and

FIG. 6 is a view similar to FIG. 1 with the leg appendages shown in an expanded position.

I claim:

The ornamental design for a riding toy figure, as shown.
